UNITED STATES PATENT OFFICE.

HENRY STAMM, OF RENTZSCHMÜHLE, NEAR GREIZ, GERMANY.

PERFECTING-MACHINE.

973,312.

Specification of Letters Patent. Patented Oct. 18, 1910.

Application filed April 19, 1907. Serial No. 369,187.

To all whom it may concern:

Be it known that I, HENRY STAMM, a subject of the Emperor of Germany, residing at Rentzschmühle, near Greiz, Germany, have invented certain new and useful Improvements in Perfecting-Machines, of which the following is a specification.

This invention relates to perfecting machines and it has for its object among others to provide a machine of this character having increased capacity accomplished by a better proportion of the paper-length printed upon to the length of the carriage-way. This proportion generally is about 1:4; *i. e.* if the sheet to be printed upon has a length of one meter, the form goes a distance of four meters for every printed sheet (two meters to and fro). By this invention the proportion is about 1:2 if the machine is driven by a crank-brace and about 1:2.6 if by a mangle rack.

A further essential advantage of the present invention is that the improved mechanical effect is not attained by oscillating impression cylinders but by cylinders which continually turn in the same direction. These latter are more easily fed with the paper and are better qualified for different sizes. The offsetting is avoided by improved means without the application of anti-offsetting paper or other auxiliary means, as for example paraffin rollers.

In the drawings Figure 1 shows a form of embodiment which is arranged for the above new anti-offsetting process. Figs. 2 to 9 show eight different successive positions of the machine according to Fig. 1, giving every position of the sheets moving through the machine.

The carriage *a* is moved to and fro as is usual in printing machines. The same carries two first impression forms *b*, *b* and two forms *c*, *c* (which produce the second impression or which perfect) which are inked by groups of rollers *g*, *h*, *i*, *k* and always one form *b* or *c* at the left hand is inked by the groups of rollers *g* or *i* given in the drawing on the left of the impression cylinders, the other forms by the groups of rollers *h* or *k* situated on the right side of the impression cylinders, so that only half of the double forms need to go through under the rollers, as is customary with certain one revolution printing machines. In this case the rollers are somewhat raised in the usual manner, while the other form, which is only partly

inked, runs through, so that they are not brought into contact therewith. It follows from this arrangement that the length of the four forms taken together is nearly equal to the length of travel (to and fro) of the carriage, and as a consequence the entire travel is used to its possibly utmost capacity. The impression cylinder *d* coöperates only with the type-forms *b*, *b* the impression-cylinder *e* only with the type-forms *c*, *c*, and the two impression-cylinders turn opposite to each other and always in the same direction without interruption.

The supply of roll-paper is arranged like in the feeding of rotary machines for changeable sizes of sheets inasmuch as the endless paper is moved off by traction-rollers *t*, *t*, cut in sheets by cutting rollers *u*, *v* (in Fig. 1) and the sheets are led in an ordinary way to the impression cylinders *d* and *e* by tapes 16, Fig. 1.

The invention is based on the ascertainment of the proper proportions regarding size and position of the impression and transmission-cylinders. At the same time it was considered, that the crossing of the paper-strips is unavoidable but there is no disorder in the sheets running to and from the impression cylinders. In Figs. 1, and 2 to 9 is shown how the offsetting is avoided in this connection without the employment of anti-offset paper-rolls.

It is to be emphasized, that the toothed wheels of the impression cylinders always catch into those of the transmission-cylinders and the latter engage with each other and that all impression-cylinders like the sheet-conveying-rollers 15 and the coacting rollers are constantly turning in the same direction as is the case with cylinders of rotary printing machines.

The transmissions from the cylinders *p* to *q* and from *q* to *e* take place in the usual manner, and a thorough description of the respective contrivances is not necessary inasmuch as they are supposed to be known and in use. The sheet is of double length measured according to the running direction as compared with an ordinary printing machine with equal travel of the carriage, *i. e.* instead of two forms *b*, *b* only a single one of nearly the same size could be printed from and inked on the latter, so that the capacity of printing of the press herein described is about double as large as with an ordinary printing machine, and as a conse-

quence the higher working order of the invention in question is proved.

The color of the groups of rollers *g* and *k* comes from one of the color-boxes *f*, *f* at the 5 ends of the machine and for the other groups from a color-box *f* near the center of the machine. Fig. 1 shows the arrangement of the central color-box, which serves for feeding the inner groups of rollers *h*, *i*.
 10 In this case the color-box is fastened above the transmission-cylinders *p*, *q* one of the latter being provided with distributing tables *o*, on which the color previously ground by rollers *l*, *l* is put by the swinging 15 color-transmission-rollers *n*, in order to be conveyed in a similar manner by one of these transmission cylinders to the inner groups of the rollers *h*, *i*.

It is evident that the peripheries of the 20 transmission-cylinders *p* and *q* and their mutual position are so arranged, that the length of the way passed by every sheet from the touching point at the type paper-forms *b*, *b* to the next forms must be exactly 25 equal to an odd number of circuits of the little impression cylinder, if the latter turns twice while running to and fro.

The arrangement for the last named purpose consists in the fact, that printing is 30 effected at the same time on two sheets from two paper rolls *x*, *x* of which one is situated on the left, the other on the right side at the ends of the machine, Fig. 1. From each of these paper-rolls the paper-strip runs in 35 the first place into one pair of take off rollers *t*, *t*, whereupon it is cut by a pair of cutting rollers *u*, *v* and the sheet, thus separated, is always led by tapes 16 around one conveying roller 15 on one side of the first 40 impression cylinder *d* and on the other side to the impression-cylinder *e* which thereupon supplies the sheet coming from the right side of the machine. The sheet coming from the right paper-roll thus runs in 45 the first place the opposite way of the sheet coming from the left roll. This longer time is required to enable the crossing of the sheets, as is seen by Figs. 2 to 9 and will be described hereafter. At the same time with 50 the sheet issuing from the impression-cylinder on the right side, which sheet is already printed on one side, an entirely new sheet from the paper-roll on the left side gets to the impression-cylinder *d*, Fig. 1, is held fast by the gripper 9 of same, while the 55 aforesaid sheet from the right side, is perfected by cylinder *d*. The new sheet serves in this manner as anti-offsetting sheet for the other one, is held fast during several 60 turns of the impression cylinder *d* by the gripper 9, until the forms *b*, *b* print same during the next back-movement of the carriage. This is so done, that those places, 65 which had received offset by the previous impression, are thereupon overprinted, and

the offset is made invisible. The impression cylinder *d* is provided for this purpose with two systems of grippers. One system 9 lays hold on the fresh sheet at the touching point of the conveying roller 15, the other system 10 remains opened up to the touching point with the transmission-cylinder *p*, where it catches the sheet coming from the right impression-cylinder. Now follows the turning of impression-cylinder *d*. After this the sheet is immediately let loose by the grippers 10, while, as said before, the sheet lying under it, is still held for a certain time by the grippers 9. At the same time the delivered perfected sheet is carried by the roller *d* and cylinder *p* to and is caught again by transmission-cylinder *q*, from which the band-transmission 80 85 90 95 100 105 riage at the right hand dead point. Fig. 4 the central position of the carriage traveling toward the left. Fig. 5 the position of the carriage at the left dead point and Fig. 6 the 5 central position of the carriage running toward the right.

The position of the single sheets simultaneously running through the machine is given by the numbered lines 1, 2, 3, 4. The 10 broken pointed lines 1 and 4 refer to those sheets coming from the right paper-roll and the full lines 2 and 3 to the sheets coming from the left paper roll.

Figs. 2 to 9 show two positions distant 15 from each other by eight positions, Fig. 2 for the first and ninth, Fig. 3 for the second and tenth and so on, so that the bracketed marks refer to that sheet which after eight further positions is in the same position as 20 the sheet marked without bracket. Hence the sheet 2 is in the first position Fig. 2 in the same state, as sheet 3 in the ninth position and sheet 2 in the eighth position Fig. 9 in the same state as sheet 3 in the 16th position 25 and so on. In the first position Fig. 2, sheet 1 is seen issuing from the right side and is already printed on the one side. Also the unprinted sheet is seen coming from the left side about to run to impression cylinder 30 *d*, while with the other impression cylinder *e* sheet 4 is about to be fully printed. In Fig. 3 the latter sheet is finished while sheet 1 is being printed together with sheet 3 serving for its anti-offsetting paper. In Fig. 4 35 the center of these sheets 1 and 3 is at the printing spot, while sheet 4 has just left impression cylinder *e*, and its head has already arrived in a serpentine winding above the conveying cylinder *p*. In Fig. 5 the head of 40 sheet 1 already runs toward the touching or contact point of the two cylinders *p* and *q*, while its hind-end has just left the form, and the other sheet, lying underneath it has been held on the impression cylinder *d*, in order 45 to be printed at the next backward movement of the forms *b*, *b*. In this position sheet 4 completely lies on conveying cylinder *p*, while the printing of sheet 2 begins with impression cylinder *e*. The simultaneously arrived new sheet in the latter position 50 and from the right side serves sheet 2 as anti-offsetting paper. In Fig. 6 cylinder *d* is in a raised position, while on the other cylinder the two sheets 2 and 4 are just 55 printing *i. e.* in the central position. In Fig. 7 the backward movement of the forms and the impression of sheet 3 the one side of which has already been printed, begins while sheet 2 has just been perfected. Sheet 4, 60 which could not be transferred in the fifth position, is as by Fig. 7 about to make a second turning with cylinder *p*, to wait till sheet 3 has left impression cylinder *d*. Sheet 3 begins leaving it in the following position 65 Fig. 8. In Fig. 9 the sheet 3 has left the

impression cylinder *d* by a half length and fully in the ninth position, to which corresponds again Fig. 2, so that in Fig. 2 the way is open to sheet 4 together with the newly arrived sheet 3, and both like sheets 1 70 and 3 previously repeat the same operation as described before.

Referring to position Fig. 7 on cylinder *q* sheet 1 fully printed, is shown going to the folding contrivance whereas the other sheet, 75 just fully printed by impression cylinder *e*, immediately follows, to also run to the folding contrivance, as is seen by Fig. 9.

The running of sheet 3, the perfecting of which begins in the position after Fig. 7 and 80 is finished in the position Fig. 9 is seen in the ninth Fig. 2, in the tenth Fig. 3 and the eleventh position Fig. 4; in the latter it gets to the impression cylinder *e* with the new sheet 4 coming from the right side. In Fig. 85 5 twelfth-position, sheet 3 begins its print with sheet 4, which serves as offsetting paper. Sheet 2 is accordingly taken along by impression cylinder *e* just at their first contact, whereas, as previously indicated, the 90 sheets running in the other direction have to make first a complete turning of the conveying cylinder.

As described before the grippers of the impression cylinder catch the new sheet 3 in 95 the position Fig. 2 and do not deliver it, before reaching the position in Fig. 8, so that it remains on the impression cylinder during three turnings. The grippers 8 Fig. 1 then open, and always after the third turning 100 deliver the sheet, the grippers 10 of the next cylinder however deliver it after the first turning.

The opening and shutting of the grippers is effected by known means as for instance 105 by sidewise movement of the gripper eccentrics and by means of particular eccentrics, which sometimes set the grippers out of operation.

If the machine is to be employed for the 110 printing of any smaller sized paper, with the exception of the velocity of the feeding rollers *t*, *t*, no other change is necessary neither with the grippers nor with the cylinders.

If half the capacity is required, the machine is made to work with one form *b* or *c* instead of two forms *b*, *b* or *c*, *c*. In this case two coloring roller-groups of four and likewise the two outside color-boxes or the 120 middle color-box may not be used.

It is indicated in Fig. 1, that the band-transmissions for the conveyance of sheets may be so arranged, as to be swinging, so that for the sake of a more convenient 125 handling the impression cylinder may be easily moved aside.

Having thus described my invention what I claim is:

1. In a perfecting machine, the combina-

- tion with the printing forms of two constantly rotating impression cylinders separated from each other and two transmission cylinders of double the size of the impression cylinders.
2. In a perfecting machine, the combination with the printing forms of two constantly rotating impression cylinders separated from each other, two transmission cylinders of double the size of the impression cylinders, means for operating said cylinders, and means for holding every unprinted sheet upon such impression cylinder during two impressions.
3. In a perfecting machine, the combination with the printing forms, of two constantly rotating impression cylinders, separated from each other, two transmission cylinders of double the size of the impression cylinders, means for operating said cylinders, means for holding every unprinted sheet upon such impression cylinder during two revolutions and means, whereby each sheet serves first as an offset paper to the sheet which has received its first impression and then receives the impression.
4. In a perfecting machine, the combination with the printing forms and right and left color boxes of two constantly rotating impression cylinders, means for actuating the same, means insuring the crossing of the two sheets running opposite to each other, and means whereby said constantly rotating impression cylinders always coöperate with the printing forms, one of which is inked by the left and the other by the right color box of each of both impression cylinders.
5. In a perfecting machine, the combination with the printing forms and right and left color boxes of two constantly rotating impression cylinders, two transmission cylinders, means for actuating the same, means insuring the crossing of the two sheets run-
- ning opposite to each other, and means whereby said constantly rotating impression cylinders always coöperate with the printing forms, one of which is inked by the left and the other by the right color box of each of both impression cylinders, combined with a system of grippers with two point-needle systems to simultaneously hold both sheets on the cylinder and to deliver them at different times.
6. In a perfecting machine, the combination with the printing forms, of two constantly rotating impression cylinders, two transmission cylinders, means for actuating the same, right and left color boxes, means insuring the crossing of the two sheets running opposite to each other, and means whereby said constantly rotating impression cylinders always coöperate with the printing forms, one of which is inked by the left and the other by the right color box of each of both impression cylinders.
7. In a perfecting machine, the combination with the printing forms, of two constantly rotating impression cylinders, right and left color boxes therefor, two transmission cylinders, means for actuating the same, means insuring the crossing of the two sheets running opposite to each other, and means whereby said constantly rotating impression cylinders always coöperate with the printing forms, one of which is inked by the left and the other by the right color box of each of both impression cylinders, combined with a system of grippers with two mechanisms to simultaneously hold both sheets on the cylinder and to deliver them at different times.

In testimony whereof I affix my signature.
HENRY STAMM.
